UNITED STATES PATENT OFFICE.

LEVI BROWN, OF RICHMOND, INDIANA, ASSIGNOR TO JOHN M. LONTZ, OF RICHMOND, INDIANA.

LAWN-MOWER.

1,031,417.

Specification of Letters Patent.

Patented July 2, 1912.

Application filed April 24, 1911. Serial No. 622,992.

To all whom it may concern:

Be it known that I, LEVI BROWN, of Richmond, Indiana, have invented a new and useful Improvement in Lawn-Mowers, which 5 invention is fully set forth in the following specification.

The present invention is an improvement in lawn mowers and particularly of the ball-bearing type in connection with some features of the invention; and the primary objects of the invention are to provide an easy running machine in which there will always be maintained a light brushing contact between the rotary cutter and the stationary 15 knife; to provide an improved connection between the ends of the stationary knife and the side frames with the object of securing the latter with the maximum rigidity; and to provide an improved connection between the side frames and the ground wheels. 20

It is of prime importance to maintain a light brushing contact between the stationary knife and the rotary cutter, and to this end it is necessary to maintain constant the 25 distance between the axis of the rotary cutter and the edge of the stationary knife. This distance is inevitably affected by wear of the bearings of the shaft of the rotary cutter, or any relative movement between the 30 side frames of the machine; and hence it is desirable to provide means to compensate for such wear of the bearings or racking of the side frames, so that the light brushing contact between the rotary cutter 35 and the stationary knife may be maintained. The old ball-bearing construction employed a cone, provided with a tapered face, mounted on the shaft of the rotary cutter, this tapered face engaging a series of balls 40 mounted in a suitable holder. With this construction it was found that there was had practically as great and as disadvantageous a variation between the axis of the rotary cutter and the edge of the stationary 45 knife as with the old "straight line" construction, for the surface of the cone engaging the balls being tapered, considerable longitudinal movement of the shaft of the rotary cutter was permitted under the varying 50 conditions of use. It has been sought to overcome this disadvantage by subjecting the bearing elements to spring pressure, in order to automatically compensate for wear and any relative movement between the side

frames of the machine, but this expedient 55 has only been partially successful; for it has been found that the springs, the maximum strength of which is always being exerted, hold the bearing elements so tightly together as to materially increase the energy 60 necessary to run the machine and to materially shorten the life of the bearings.

Directed to this objection, one of the objects of the present invention is to automatically control the application of pressure 65 to the bearing elements so that the light running of the machine is maintained under all conditions of use. Briefly stated, this feature of the invention consists in the provision of a controlling means whereby, when 70 the bearing elements have been brought into proper operative relation to compensate for any wear of the parts or racking of the frame, this controlling means automatically operates to immobilize one of said elements 75 with relation to the shaft, and thus prevent binding of the bearings. In the preferred construction, the bearing elements are subject to spring pressure, the springs acting to bring said elements into proper operative 80 relation, and the controlling means automatically operates to prevent any further application of the spring power which would act to unnecessarily and to disadvantageously bind the bearings. The bearings are 85 thus substantially relieved of the spring pressure by the controlling means until further wear of the parts or racking of the frame requires a further application of the spring pressure on the bearings to compensate 90 therefor. The preferred form of controlling means employed is a collapsible sleeve which is introduced between the spring and one of the bearing elements—preferably the cone carried by the shaft of 95 the rotary cutter—which sleeve is axially movable in one direction by the spring until the desired engagement between the bearing elements is effected, at which time the sleeve is caused to automatically and securely grip 100 the shaft by a reflex action of the spring pressure transmitted to the sleeve through the ball bearings and the cone; and hence the bearings are substantially relieved and any further application of the spring pressure thereto is prevented until further wear 105 or racking of the frame requires.

A further object of the invention is to

increase the rigidity of the frame, looking to the general improvement of the device. It has heretofore been experienced that the severe usage to which machines of this character are subject has resulted in the loosening of the connections of the ground wheels to the side frames, with the result that said frames have been subject to increased strain and racking. One feature of the present 10 object resides in so mounting the ground wheels on the side frames as to insure practical rigidity between these parts. A second feature of this object resides in an improved means for connecting the stationary knife 15 to the side frames, whereby the latter are held in practical and unalterable parallelism under all conditions of usage; and the stationary knife is readily adjustable, with great exactness, toward and from the rotary cutter.

20 The provision of the controlling means for the spring pressure, obviates the necessity for any adjustment of the rotary knives after the machine leaves the factory, and 25 indeed any adjustment is impossible unless the machine is dismantled. It will be understood that this controlling means may be employed with bearings in connection with which no spring is used.

30 The invention will be better understood by reference to the accompanying drawings, which illustrate one embodiment of the inventive idea, and wherein—

Figure 1 is a top plan view, partly in 35 section, of the improved lawn mower; Fig. 2 is a view of the various elements carried on each end of the shaft of the rotary cutter, said elements being pulled out or extended one from the other; Fig. 3 illustrates 40 in section and end elevation the cone bearing member which is carried by the shaft of the rotary cutter; Fig. 4 illustrates in section and end elevation the split sleeve which is the means for controlling the 45 application of the spring pressure; Fig. 5 is an enlarged sectional view, partly in elevation, illustrating one end of the shaft of the rotary cutter and several of the elements carried thereby; Fig. 6 is an enlarged section 50 view partly in elevation illustrating the means for rigidly mounting a ground wheel to one of the side frames of the machine; Fig. 7 is an enlarged perspective view of the sleeve and the cone member 55 shown in section in Fig. 6. Fig. 8 is a sectional view, partly in elevation, illustrating the means for connecting the stationary knife to the side frames of the machine; and Fig. 9 is a perspective view illustrating the means for rigidly securing together the stationary knife and the side 60 frames of the machine.

Referring to the drawings, 10, 10 indicate two side frames of the machine on 65 which are mounted any suitable ground

wheels 11, stationary knife 12 and roller 13, said side frames being connected together by rod 14.

The shaft for the rotary cutter blades 15 is indicated by 16. Said shaft is mounted 70 in the side frames 10, and on each end thereof carries a pinion 17, which engages rack 18 carried by the ground wheel 11; and a pawl 19 of any well known or desired construction passes through a perforation 75 in the end of shaft 16 and engages depressions on the inside of said pinion, all as is usual.

The blades of the rotary cutter are suitably secured to hubs 20 and these latter are 80 fixed to shaft 16 in any desired manner. Engaging the outside face of the hub on each side of the machine is a casing 21 within which is carried a spring 22 of any suitable construction, one end of which 85 spring engages said casing and the other end a split sleeve 23 encircling the end of shaft 16. This split sleeve, which is preferably of phosphor bronze, projects into and is slidable along shaft 16 with a bearing 90 element or cone 24. This cone is provided with a tapered face which engages suitable supporting means, preferably a plurality of bearing balls 25 carried by a ball-cup or raceway 26. While the cone 24 95 and the split sleeve 23 are movable longitudinally of the shaft 16, they are prevented from rotating relatively thereto by pin 27 which passes through a transverse perforation in shaft 16. As will be more fully appreciated from an inspection of Figs. 2 and 100 4, the split sleeve 23 is tapered in cross section, and is made flexible by the provision of splits or slots 28 provided in the thickened end of said sleeve and splits or slots 105 29 provided in the thinner end of said sleeve; and said pin 27 preferably engages in said slots 28 and in slots 30 provided in cone 24 to prevent the rotation, referred to, of said split sleeve and cone. 110

From the foregoing, it will be understood that should the side frames 10 move relatively one to the other, or should the parts become worn, the spring 22 will operate to move the bearing member 24 to compensate 115 for this movement of the side frames or the wear of the parts and to maintain constant the distance between the axis of the shaft on which the rotary cutter is mounted and the edge of the stationary knife. This pressure is transmitted to said cone 24 through the split sleeve 23, and as soon as sufficient movement of the cone 24 is had to compensate for the relative movement of the side frames or the wear of the parts, it is desired that the application of the spring pressure be cut off so that there will be no unnecessary binding between the bearing elements, which binding would disadvantageously affect the light running of the 120 125 130 machine.

machine. This cutting off or control of the spring pressure is effected by the split sleeve 23, and takes place by a reflex action of the spring pressure which is transmitted to the 5 split sleeve through the balls 25 and cone member 24, which latter acts on the thinner end of said split sleeve and causes it to promptly and securely grip the shaft 16 as soon as the racking of the frame or wear 10 of the parts has been compensated for. Thus the bearings are relieved and further application of the spring pressure to the bearing elements is prevented until further wear or racking of the frame demands it. 15 The provision of this controlling means or split sleeve makes it possible to use a very much lighter and cheaper spring than has heretofore been possible. Formerly it was necessary to provide a spring of sufficient 20 strength to move the parts a sufficient distance under all the varying conditions of usage, with the result that too great an application of spring power was had, resulting in the disadvantages above noted. 25 The means for mounting the ground wheels 11 on the side frames 10 are illustrated particularly in Figs. 1, 6 and 7. These means have for their primary object to effectively and rigidly connect the ground 30 wheels to said side frames. To this end a bolt 31, which is screw-threaded at one end, passes through each side frame and is connected to the ground wheel by the means hereafter described. This bolt has a head 35 32 which is provided with a depression in which a suitable projection 33 on the side frame 10 is adapted to engage to position said bolt. A cone 34 engages around an enlarged part of said bolt 31 and the tapered 40 face of this cone constitutes the bearing surface for the balls 35 carried in the ball holder 36. This cone is provided with a plurality of recesses 37, preferably diametrically arranged, in which engage projections 38 provided on a hollow sleeve 39. This hollow 45 sleeve has internal screw threads 40 and external screw threads 41 provided at one end thereof. A screw threaded cone 42 engages the screw threads 41 on said hollow sleeve, 50 and is provided with a tapered surface which forms a bearing for the balls 43 carried by the holder 44. This cone member 42 is provided with a plurality of transverse perforations 45 which are adapted to be brought 55 into alignment with a slot 46 arranged in the end of bolt 31 and slots 47 provided in the end of hollow sleeve 39. When the ground 60 wheel 11 is secured to the appropriate side frame 10 a pin 48 is passed through the perforation in the cone member 42 which is in alignment with the slots in the bolt and hollow sleeve and thus the parts are held fixedly in position. In assembling these parts the bolt 31 is first passed through the side frame 65 10 and the depression in the head 32 is en-

gaged with the projection 33 on said side frame. The cone 34 is then slipped over the bolt 31 and into the position shown in Fig. 6, after which the hollow sleeve 39 is screwed onto the bolt 31, the internal screw threads 70 40 of said hollow sleeve engaging the screw threads on said bolt. When said sleeve has been screwed down so that the projections 38 thereon are in close proximity to the recesses 37 in the cone member 34, said sleeve 75 is sprung so that said projections 38 engage the recesses 37. The continued rotation of the sleeve 39 then results in the simultaneous rotation of the cone 34 and, as will be appreciated, this rotation will act to fixedly 80 clamp the bolt 31 to the side frame 10 and also to tightly bind said side frame, bolt 31, sleeve 39, and the cone 34 together. The balls 35 carried by the ball holder 36 are then engaged with the cone 34 after which 85 the ground wheel 11 is placed in the position shown in Fig. 1, a flange 49 carried by said wheel engaging the ball holder 36. This flange is provided with a socket 50 which is adapted to receive the holder 44 90 carrying the balls 43. After this holder is placed in position the cone 42 is screwed onto the sleeve 39 until it is in proper position for the passing of the pin 48 through the aligned slots in bolt 31 and sleeve 39, and one of the perforations 45 in said cone. 95 When the parts are thus secured together, the ground wheels will be rigidly and securely held to the side frames 10 and under all conditions of usage it will be found practically impossible to loosen the ground 100 wheels from said side frames. Any wear of the wheel bearings that may occur during the life of the mower may be taken up by removing pin 48 and tightening cone 42, and then passing pin 48 through slots 46 and 47 and the perforation in cone 42 which is in alignment therewith. To further insure the rigidity of said side frames, the stationary 105 knife 12, which has a cutting edge 52, is 110 provided with means for maintaining said side frames in accurate and fixed parallelism. On each end of said knife there are provided two parallel flanges 53 between which a bearing portion 54 of each side 115 frame engages. This bearing 54 is provided with carefully machined faces which engage the inside of flanges 53 which are also carefully machined. A cylindrical pin 55 passes through said flanges 53; and surfaces 56, 120 preferably formed integrally with the stationary knife, incline downwardly from said pin on each side thereof. The bearing portion 54 is provided in its lower face with an elongated semi-circular recess 57 which is 125 adapted to engage the pin 55 which constitutes a fulcrum ridge, as best illustrated in Figs. 8 and 9. Bolts 58 provided with nuts 59 pass through suitable openings in said stationary knife on either side of said pin or 130

fulcrum ridge 55, and through enlarged portion 54 and fixedly hold said knife in any position to which it may be adjusted. The provision of this cylindrical bearing insures that any movement of the stationary knife to adjust the same will always be on the same radius; and it will be understood that to adjust said knife to any desired position it is only necessary to loosen one bolt and tighten the other, and vice-versa.

10 In machines constructed as heretofore described, the device is adjusted at the factory once for all. Only the stationary knife 12, the roller 13 and the ground wheels 11 can be readily reached. All the other parts are inaccessible; no outside screws are presented which would invite tinkering on the part of operators; and, unless the machine is dismantled, no adjustments—other than those 15 affecting knife 12, roller 13 and the ground wheels 11—are possible. Further, the provision of the controlling means or split sleeve 23 is also advantageous in that the shaft of the rotary cutter need not be made 20 so perfectly and to the exact proportions heretofore required; and this without any sacrifice either of the durability or easy operation of the machine.

While as herein described and illustrated, 30 the means for maintaining constant the distance between the axis of the rotary cutter and the edge of the stationary knife are indicated as being duplicated on each end of the shaft of the rotary cutter, it has been 35 found that satisfactory results have been obtained with said means arranged only on one end of the shaft of said rotary cutter.

While the preferred construction of the device has been heretofore specifically described, it is to be understood that the invention 40 is not limited to the particular means illustrated, and that changes may be made without departing from the spirit of the invention, the scope of which is indicated in 45 the appended claims. For example, the springs, which have been described for automatically taking up wear in the bearings, might be omitted, and other means for taking up such wear substituted.

50 The stationary knife mounting and the ground wheel mounting, while herein described and illustrated, are not herein claimed, the same constituting the subject-matter of divisional applications Serial Nos. 55 652,939 and 652,940, respectively, both filed October 5th, 1911.

What I claim is:—

60 1. In a machine of the character described, the combination of a frame, a stationary knife, a shaft, a cutter mounted thereon, a supporting element for said shaft, a bearing element mounted on said shaft and engaging said supporting element, a spring arranged to move one of said elements with 65 relation to the other, and means interposed

between said spring and its associated element for controlling the application of power of said spring.

2. In a machine of the character described, 70 the combination of a frame, a stationary knife, a shaft, a cutter mounted thereon, a supporting element for said shaft, a bearing element mounted on said shaft and engaging said supporting element, a spring arranged to move one of said elements with 75 relation to the other, and means mounted on said shaft and interposed between said spring and said bearing element and controlling the application of power of said spring.

3. In a machine of the character described, 80 the combination of a frame, a stationary knife, a shaft, a cutter mounted thereon, a supporting element for said shaft, a bearing element mounted on said shaft and engaging 85 said supporting element, a spring arranged to move one of said elements with relation to the other, and means engaging and movable with said bearing element and controlling the application of power of said 90 spring.

4. In a machine of the character described, 95 the combination of a frame; a stationary knife, a shaft, a cutter mounted thereon, a supporting element for said shaft, a bearing element mounted on said shaft and engaging 100 said supporting element, a spring arranged to move one of said elements with relation to the other, and a split sleeve interposed between said spring and its associated element for controlling the application 105 of power of said spring.

5. In a machine of the character described, 110 the combination of a frame, a stationary knife, a shaft, a cutter mounted thereon, a supporting element for said shaft, a bearing element mounted on said shaft and engaging 115 said supporting element, a spring arranged to move one of said elements with relation to the other, and a split sleeve 120 mounted on said shaft and interposed between said spring and said bearing element and controlling the application of power of said spring.

6. In a machine of the character described, 125 the combination of a frame, a stationary knife, a shaft, a cutter mounted thereon, a supporting element for said shaft, a bearing element mounted on said shaft and engaging 130 said supporting element, a spring arranged to move one of said elements with relation to the other, and a split sleeve engaging and movable with said bearing element and controlling the application of power of said spring.

7. In a machine of the character described, 135 the combination of a frame, a stationary knife, a shaft, a cutter mounted thereon, a ball-bearing for said shaft, a cone mounted on said shaft and engaging said ball-bear-

- ing, a spring encircling said shaft and acting on said cone, a split sleeve interposed between said spring and cone and movable longitudinally of said shaft with said cone, and means preventing the rotation of said split sleeve and cone relatively to said shaft.
8. In a lawn mower, the combination with a rotary cutter and an end frame of the machine, of a ball-bearing supporting one end of the shaft of the cutter in said frame, said bearing comprising two ball-contacting elements, one a ball cup or raceway associated with one of said parts, and the other a cone associated with the other of said parts, and a gang of bearing balls interposed between said ball-contacting elements; and means adapted to exert yielding pressure tending to relatively move said ball-contacting elements toward each other until both make firm contact with the balls and to thereupon automatically diminish or relieve said pressure.
9. In a machine of the character described, the combination of a frame, a stationary knife, a shaft, a cutter mounted thereon, a supporting element for said shaft, a bearing element mounted on said shaft and engaging said supporting element, means associated with one of said elements automatically operating to immobilize said element relatively to said shaft, and means for adjusting one of said elements relatively to the other.
10. In a machine of the character described, the combination of a frame, a stationary knife, a shaft, a cutter mounted thereon, a supporting element for said shaft, a bearing element mounted on said shaft and engaging said supporting element, means interposed between one of said elements and said shaft automatically operating to immobilize said element relatively to said shaft, and means for adjusting one of said elements relatively to the other.
11. In a machine of the character described, the combination of a frame, a stationary knife, a shaft, a cutter mounted thereon, a supporting element for said shaft, a bearing element mounted on said shaft and engaging said supporting element, means associated with one of said elements automatically operating to immobilize said element relatively to said shaft, and means for adjusting one of said elements relatively to the other operating through said associated means.
12. In a machine of the character described, the combination of a frame, a stationary knife, a shaft, a cutter mounted thereon, a supporting element for said shaft, a bearing element mounted on said shaft and engaging said supporting element, means interposed between one of said elements and said shaft automatically operating to immobilize said element relatively to said shaft, and means for adjusting one of said elements relatively to the other operating through said interposed means.
13. In a machine of the character described, the combination of a frame, a stationary knife, a shaft, a cutter mounted thereon, a supporting element for said shaft, a bearing element mounted on said shaft and engaging said supporting element, a collapsible sleeve associated with one of said elements automatically operating to immobilize said element relatively to said shaft, and means operating through said collapsible sleeve for adjusting one of said elements relatively to the other.
14. In a machine of the character described, the combination of a frame, a stationary knife, a shaft, a cutter mounted thereon, a supporting element for said shaft, a bearing element mounted on said shaft and engaging said supporting element, a collapsible sleeve interposed between one of said elements and said shaft automatically operating to immobilize said element relatively to said shaft, and means operating through said collapsible sleeve for adjusting one of said elements relatively to the other.
15. In a machine of the character described, the combination of a frame, a stationary knife, a shaft, a cutter mounted thereon, a supporting element for said shaft, a cone bearing mounted on said shaft and engaging said supporting element, a collapsible sleeve interposed between said cone and said shaft automatically operating to immobilize said cone relatively to said shaft, and means operating through said collapsible sleeve for adjusting said cone relatively to said supporting element.

In testimony whereof I have signed this 195
specification in the presence of two sub-
scribing witnesses.

LEVI BROWN.
